UNITED STATES PATENT OFFICE

EARL W. LESHER, OF LAKewood, OHIO

WALL CONSTRUCTION AND SECTIONS THEREFOR

Application filed January 27, 1927. Serial No. 163,888.

This invention relates to a wall construction, formed from sections or units. In one application of the invention it may constitute the exposed surface or wall and in such use 5 its face may be treated for decorative effect or painted or papered. In another application of the invention, either for the outside or inside walls (or both) of a building, the sectional wall forms a base for a coating of suitable material, for example plastic material.

One object of the invention is to provide an improved sectional wall or wall surface which is relatively cheap, light, easily handled and formed of a material having relatively high insulating characteristics to prevent the transfer of heat.

Another object of the invention is to provide a construction having a sectional wall which is relatively simple and economical and 20 in which the sections are so inter-related along their side edges that buckling or distortion thereof between the wall studding and ultimate damage to the wall is prevented.

Another object of the invention is to provide an improved wall having a base for the coating so constructed that expansion may 25 take place without causing distortion.

A further object of the invention is to provide a wall construction having an improved 30 base, whereby a finishing coat may be readily applied and firmly held on the base when hardening of the coating material takes place.

Other objects of the invention will be apparent to those skilled in the art to which 35 my invention relates from the following description taken in connection with the accompanying drawings, wherein

Fig. 1 is a perspective view of the interior of a building having a wall construction embodying my invention.

Fig. 2 is a fragmentary elevation of the wall.

Fig. 3 is a plan view of the parts shown in Fig. 2.

Fig. 4 is a fragmentary view in perspective of one of the wall sections.

Fig. 5 is a section on the line 5—5 of Fig. 4.

Fig. 6 is a view of an interconnecting device.

Fig. 7 is a view similar to Fig. 4, but show-

ing a different form of interconnecting device.

Fig. 8 is a section on the line 8—8 of Fig. 7.

Fig. 9 is a view similar to Figs. 4 and 7, but showing another form of interconnecting device.

Fig. 10 is a section on the line 10—10 of Fig. 9.

Fig. 11 is a view similar to Figs. 4, 7 and 9, but showing another form of interconnecting device.

Fig. 12 is a section on the line 12—12 of Fig. 11.

Fig. 13 is a fragmentary view, in perspective, showing a further modification of my invention.

Fig. 14 is a section on the line 14—14 of Fig. 13.

Fig. 15 is a fragmentary section showing a further modification of the form of construction illustrated in Figs. 13 and 14.

Fig. 16 is a fragmentary view, in perspective, showing another form of construction.

Fig. 17 is a section on the line 17—17 of Fig. 16.

Fig. 18 is a plan view of the parts shown in Figs. 16 and 17.

Fig. 19 is a fragmentary view, in perspective, showing a still further modified form of construction.

Fig. 20 is a section on the line 20—20 of Fig. 19.

Fig. 21 is a plan view of the parts shown in Figs. 19 and 20.

Fig. 22 is a fragmentary view showing a wall with my improved base applied to both sides of the studding.

Fig. 23 is a fragmentary view showing one way of forming certain abutting edges of a base section.

My improved construction is adapted for use as a surface, such as a wall, for example, the side walls of a building, or as the base for a coating where the latter is to form the

wall surface, either interiorly or exteriorly of a building. When my improved construction is used for exterior walls, I prefer to employ in connection therewith a certain arrangement of the base sections and certain structural features to effect keying of the

90

95

100

surfacing or coating material. This latter species of my invention will form the subject matter of a separate application. In this application I show the interior wall of a building, but it will be understood that as far as the scope of my invention is concerned, the construction herein disclosed and claimed may constitute either the outside or inside wall of a building, or the construction may be such that both the outside and inside faces thereof may be provided by the use of my improved wall sections or units, as shown in Fig. 22.

The wall A comprises uprights or studding 15 1 preferably having their centers approximately 16" apart, a wall 2 consisting of sheets of cellular material, such as "insulite", "celotex" or "masonite" cut into sections or units, for example 48" by 16" or 48" by 24" 20 preferably one-half inch in thickness, and nailed or otherwise secured to the studding 1, as shown at 3, in edge to edge relation. For an interior wall, such sections constitute a (1) wall or wall surface, as will later appear of 25 (2) base for a finishing surface or coating B of plaster, paint, paper and the like (Fig. 1); for an exterior wall, such sections constitute a base for cement or other plastic material; although in either arrangement the base may 30 be otherwise surfaced or coated without departing from the invention.

In exterior wall construction I may use two thicknesses or layers of the sheet material 2, and secure them together face to face by a 35 weatherproof cement, such as a liquid asphalt to insure insulation against dampness. But this arrangement will be included in the separate application (already referred to) for which reason it is not shown or claimed 40 herein.

The materials referred to are made from wood pulp, corn stalks, sugar cane or other cellular stock suitably treated and rolled or compressed into sheet form of any desired 45 thickness (but preferably one-half inch thickness) and cut into any desired size. Such fabricated materials have a number of advantageous characteristics for use as a wall or as a base where the surface is to constitute 50 a coating such as plastic material and the like. The sections 2 made from any of these materials are relatively light and enable a workman to carry and handle relatively large sheets thereof in a ready manner. The sections 55 form an insulating sheathing to exclude and prevent the escape of air and to prevent the transfer of heat by conduction in either direction. The material also lends itself to ready impregnation with moisture-proofing 60 material, such as heated asphalt in liquid condition, and absorbs or permits impregnation to a limited extent of the plastic material constituting the finishing coat B so that in the hardening of the latter a vacuum is set 65 up between the base sections and the coating

to maintain the latter in fixed relation to the base. The material of which the sections are made permits it or its edges to be readily shaped or formed when being fabricated or in its completed state, the material may be 70 cut by a saw or other tool into different sizes and the edges of the sections may be acted upon by a suitable tool, such as a milling cutter to shape them as shown herein; also, such material permits, in a ready manner, 75 the projection into it or between its fibers interconnecting devices such as relatively thin plates, as will later appear, without weakening 80 and causing a breaking down of the material; also by reason of its cellular form the material is compressible or yieldable and expandable to a limited extent.

4 indicates interlocking devices disposed between the aligned, abutting edges 2^a of the sections, the purpose being to form a construction wherein the base sections are suitably maintained in their planes without the use of structural supports, such as headers, to resist pressure incident to the application 85 of the coating material thereto or distortion or buckling due to expansion or contraction. I have shown herein two forms of interconnecting devices and several species of each form. One form 4^a is shown in Figs. 2 to 12, inclusive, and consists of one or more members supported on and projecting from one horizontal or side edge 2^a of each section 2 and adapted to be projected into the adjoining horizontal or side edge 2^a of the adjacent section when the latter is placed in position; and the other form 4^b is shown in Figs. 13 to 121, inclusive, and consists of elements on certain or all of the edges 2^a of each section 2' so constructed and arranged that when two or more sections 2' are positioned on the studding 1 substantially edge to edge the elements on one edge of one section will be complementary to the elements on the adjoining edge of the adjacent section and therefore such edges will interlock to prevent disalignment, distortion thereof or lateral movement, one edge relative to the other edge.

Referring to the first form of construction (4^a), Figs. 2, 3, 4, 5 and 6 show one species of interconnecting device consisting of a relatively thin plate 5 embedded in the material of each section 2 preferably centrally between its opposite faces and having a portion 5^a which extends outwardly in the plane of the section from one side edge 2^a thereof for projection into the side edge 2^a of the adjacent section 2. The plate 5 is shaped so that the projection 5^a is relatively sharp, which permits it to be readily embedded in the material of the adjacent section when the latter 125 is positioned and nailed to the studding 1. I prefer to mount the plates 5 in the upper horizontal edge of each section and to provide a plurality thereof on each section. Where the studding 1 is spaced 16" and the 130

sections cut to lengths of 48", I prefer to provide three plates 5 and space them so that each will be arranged substantially midway between adjacent studs. As shown in the drawings, I prefer to use a plate of rectangular shape and so embed it in the material of the section that only one corner of the plate projects outwardly. In this arrangement one long and one short side edge of the plate is utilized to resist the inward thrust incident to the projection of the corner 5^a into the adjacent section (as shown at 5' in Figs. 2 and 4). As the edges of the projection 5^a are shorter in length than the edges embedded in the section, the resistance along these latter edges will exceed the resistance set up by the edges of the projection 5^a; accordingly, each plate 5 will remain in operative position when the sections 2 are being applied to the studding 1, as shown in Figs. 1 and 2.

In Figs. 7 and 8 the interconnecting device comprises a U-shaped plate 6 straddling the edge 2^a of the section 2 and having a portion up-set to form a projection 6^a, the slits 25 in the plate being arranged to position the projection centrally between the faces of the plate.

In Figs. 9 and 10, the interconnecting device 7 comprises a plate 7^a arranged to engage the side edge 2^a of the section 2 and having along its inner edge a depending member 7^b embedded in the material of the section and an up-standing projection 7^c which extends into the material of the adjacent section 2, and having along its outer edge alignment members 7^d, 7^e, one extending upwardly and the other downwardly so as to engage the outer faces of the adjacent sections 2. As will be understood, the members 7^d, 7^e, co-operate with each other and the member 7^b and projection 7^c to prevent disalignment and distortion of the sections 2, and accordingly supplement the action of the member 7^b and projection 7^c. The free edge 45 of the projection 7^c is inclined to provide a relatively sharp end.

In Figs. 11 and 12 the interconnecting device 8 comprises a relatively wide plate 8^a embedded in the material of the section and provided with an extension 8^b, which projects into the material of the adjacent section, and wings 8^c bent at right angles to the plate 8^a so as to engage the side edge 2^a of the section 2 to resist inward movement of the plate. The wings 8^c are preferably extended laterally in opposite directions.

In Figs. 13 to 21, the interconnecting devices 4^b are provided by shaping the abutting horizontal edges of the sections to provide complementary interlocking elements which co-act to prevent relative lateral movement, disalignment or distortion between the base sections, such elements constituting the equivalents of the devices shown in Figs. 2 to 65 12, inclusive.

In Figs. 13 and 14, the opposite horizontal side edges 2^a of each section 2' are beveled on planes parallel to each other, this arrangement providing a complementary fit between the upper edge 2^a of one section 2' and the lower edge 2^a of the next section 2'. In this arrangement, the lower edge or portion of each section 2' is held against outward flexing and the upper edge or portion of each section is held against inward flexing. To prevent the flexing of these edges in either direction I prefer to provide between the sections supplemental connectors 10, for example, a connector similar to that shown in Figs. 2 to 6, inclusive, as shown in Fig. 15.

In Figs. 16, 17 and 18, the opposite faces of the section 2' along each horizontal edge are formed with spaced recesses 11, each preferably having a depth equal to one half the thickness of the section and a length equal to the length of the wall or land 11^a separating them. Due to the fact that each recess 11 on either face of the section is opposite a wall 11^a on the same face, it will be seen that when two or more sections are positioned edge to edge, on the studding 1 the recesses 11 and walls 11^a will be complementary and hence permit their interlocking one with another, as shown in Fig. 17. In this form of construction the inner faces of the walls or lands 11^a on adjacent sections abut, and as these walls are alternately arranged they co-act to prevent distortion or lateral movement of one section relative to the other.

In Figs. 19, 20, 21 I show another form of complementary interlocking or interconnecting elements, in which portions of each horizontal edge 2^a of each section 2' are alternately beveled in opposite directions, as shown at 12, 12^a. These beveled portions are of uniform length and each beveled portion 12 or 12^a on one edge of the section 2' is parallel to a beveled portion 12 or 12^a, respectively, on the other edge of the section opposite thereto. As a result of this arrangement, each edge 2^a is provided with alternately arranged recesses and lands 12' which are complementary to the adjoining edge of the adjacent section. As shown, each land 12' on one horizontal edge of one section fits between adjoining lands 12' on the adjoining horizontal edge of the adjacent section and the beveled faces or elements 12 or 12^a abut face to face, so that such lands co-act to prevent distortion or lateral movement of one section relative to the other.

In the forms of construction shown in Figs. 16 to 21, inclusive, it will be noted that the sections are uniform in construction; for example, along one edge of the section 2', on one face of the section a land is disposed at one end and a recess at its other end and on the other face, the lands and recesses at the ends of the section are reversed; whereas along the opposite edge of the section, the lands and recesses on corresponding faces of the section

are reversed, respectively; and in Figs. 19, 20 and 21, the abutting face on the edge at one end of the section is beveled oppositely of the abutting face at the other end thereof, while on the opposite edge of the section the beveled faces are reversed, respectively. This uniformity of construction facilitates manufacture, crating and shipping of the sections and also their positioning one relative to the other on the studding.

The form of construction shown in Figs. 19, 20 and 21 is advantageous in that the interconnecting walls 12-12^a are capable of absorbing or compensating for any expansion that may take place in the material, for example due to absorption of moisture from the plastic material when the latter is applied to the sections. When such expansion takes place, the cellular characteristics of the material permit of limited compression of the walls 12-12^a and slight lateral flexing of the outer portions of the walls or lands 12' so that such expansion is fully compensated for and any resulting pressure tending to move or distort either section laterally is prevented by the co-action of the oppositely inclined faces 12-12^a, of the adjacent sections.

In the form of construction shown in Figs. 13 to 21, inclusive, I preferably provide for keying the surfacing material. The keying is secured by slightly cutting away a corner or corners along one horizontal edge of each section, or the perimeter of the resulting edges formed by the interlocking elements 11-11^a and 12-12^a, as shown at 13, thereby forming a keying groove so that the plastic material may adhere to the fibers exposed in the joints between the sections.

To reduce the operations in cutting to provide the keying groove, I prefer to start the bevel face 12 or 12^a at the point α , as shown in Fig. 23, inwardly of one face of the section.

In applying the sections 2 or 2' to the studding 1, I may position them out of alignment or off-set one with another vertically, as shown in Figs. 1 and 2, or the sections may be disposed in vertical alignment, that is, with their end edges terminating along the center lines of the same studs. The sections 2' shown in Figs. 16 to 21, inclusive, are preferably secured to the studding 1, by nails 3 or other suitable means.

In the present construction I have shown the interlocking devices along two opposite edges of each section. It will be understood that certain thereof particularly, the form shown in Figs. 16 to 21, inclusive, are adapted for use along all four sides of the section, but such construction and arrangement will form the subject-matter of a separate application.

The forms of construction shown in Figs. 13 to 21, inclusive, have the further advantage of providing (1) a sectional wall in

which the portions of adjacent sections overlap each other to form a lapped joint and hence prevent the passage of air or heat through the joint and (2) an arrangement in which the securing devices for securing the sections to the studding 1 may be covered or concealed from view; that is, in the first referred to form, such devices extend through the lands 11^a on the face of the sections adjacent the studding and in the second referred to form the securing devices extend through the lands 12' on the sections adjacent the studding 1.

From the foregoing description it will be seen that the sections forming the wall or wall surface or a base for a coating are connected together intermediate the spaced studding to impart rigidity to the sheet sections, whereby one is braced by the other; also in the forms of construction shown in Figs. 16 to 21, inclusive, two opposite edges between adjacent sections have inter-connecting or inter-locking elements throughout their lengths, this being the preferred form of construction, altho in the broader aspects of the invention these elements need extend along a portion of the section edges. As already set forth, the inter-connecting devices prevent distortion or buckling and eliminate the use of headers or other supports between the studding, thus simplifying the wall construction and reducing the cost thereof and labor required. By preventing lateral movement or yielding of the sections between their abutting edges, any and all pressure resulting in the application of a plaster coating is adequately resisted and by preventing distortion due to expansion or contraction, the wall remains in a plane throughout its entire extent and danger of damaging a plastic coat, when the latter is applied, is avoided.

To those skilled in the art to which my invention relates many changes in construction and widely differing embodiments and applications of my invention will suggest themselves without departing from the spirit and scope thereof. My disclosures and the description herein are purely illustrative and are not intended to be in any sense limiting.

What I claim is:

1. A wall construction comprising spaced members, sections of material each extending from one member to another member and secured to said members, and means carried by and disposed between the adjoining edges of the sections and extending at right angles to said members for preventing movement of said edges laterally one relative to the other, between said members.

2. A wall construction comprising spaced members, sections of material each extending from one member to another member and secured to said members, and means

120

125

130

carried by one edge of each section and arranged to project into the adjoining edge of an adjacent section for preventing movement of said edges laterally one relative to the other, between said members.

5 3. A wall construction comprising spaced members, sections of material each extending from one member to another member and secured to said members, and means carried by one edge of each section between adjacent members and arranged to project into the adjoining edge of an adjacent section for preventing movement of said edges laterally one relative to the other, between said members.

10 4. A wall construction comprising spaced members, sections of material each extending from one member to another member and secured to said members, and devices carried by the adjoining edges of adjacent sections 20 and inter-related with each other to prevent movement of said edges laterally one relative to the other, between said members.

15 5. A wall construction comprising spaced studding, and sections of sheet material each extending from one studding to another studding and secured thereto, the abutting horizontal edges of the sections being shaped to provide complementary elements which co-act to prevent lateral movement of the edges one relative to the other, between the studding.

20 6. A wall construction as claimed in claim 5 in which one outer edge of each section is 25 cut away to form a keying groove between the sections.

25 7. A wall construction comprising spaced studding, and sections of sheet material each extending from one studding to another studding and secured thereto, opposite side edges of each section being formed with series of alternately arranged recesses and lands, the lands on one side edge being aligned with the recesses on the opposite edge, whereby adjacent sections are complementary one to the other.

30 8. A wall construction as claimed in claim 7 in which the faces of the recesses and faces of the lands co-act to prevent lateral movement of the edges of the sections one relative 35 to the other, between their supporting studding.

35 9. A section of sheet material in which portions of two opposite edges are beveled on planes parallel to each other from one face 50 of the section to the opposite face thereof, said portions being beveled in on each edge opposite directions.

40 10. A section of sheet material provided along two opposite edges with faces beveled from one face of the section to its opposite face in opposite directions, said faces being alternately arranged and of uniform 45 length.

45 11. In a wall construction, the combination 50 of spaced studding, and a wall comprising

sections each extending from one studding to another studding and secured to said studding in edge to edge relation and each provided along two of its opposite edges between the studding with alternately arranged recesses and lands, those on one edge of one section being complementary to those on the edge of the adjacent section.

55 12. In a wall construction, the combination of spaced studding, and a wall comprising sections secured to said studding in edge to edge relation, two opposite side edges of each section being provided with alternately arranged transversely inclined portions to form series of spaced projections extending 60 outwardly in line with the opposite faces of the section along each side edge, the projections forming one series alternating with those forming the other series along each of said edges, the planes of the inclined faces of each series intersecting the planes of the faces of the adjacent series.

65 13. A wall construction as claimed in claim 12 in which the wall sections are formed from cellular stock.

70 14. A section of material for a wall having along one side edge and upon the opposite faces of said section series of outwardly projecting correspondingly shaped members, the members of each series having corresponding faces in the plane of one face of the section and their other corresponding faces being inclined transversely inwardly to the opposite face of the section and the members of one series alternating with and being oppositely disposed relative to the members of the other series.

75 15. A section as claimed in claim 14 in which the opposite side edge of the section is provided with corresponding series of projections.

80 16. In a wall construction, the combination of spaced studding, and a wall secured to said studding, said wall comprising sections each having along two of its opposite side edges series of transversely inclined faces, one series along one edge being inclined oppositely to the other series along said edge and the faces on the opposite edge being similarly arranged with respect to each other but each out of line with a corresponding face on the first edge, whereby the sections are of uniform construction and one edge of one section is complementary to the edge of the adjacent section.

85 17. In testimony whereof, I have hereunto subscribed my name.

EARL W. LESHER.
